UNITED STATES PATENT OFFICE

AUSTIN A. BENEDICT, OF MERRILL, WISCONSIN, ASSIGNOR OF THIRTY-FIVE PER CENT
TO DAVE P. RAJEC, OF MERRILL, WISCONSIN

COMBINATION VISE AND GRIPPING TOOL

Application filed December 12, 1927. Serial No. 239,517.

This invention relates to a combination vise and gripping tool.

Objects of this invention are to provide a novel form of gripping tool which is adapted to engage bolts, keys, or pins, whether or not any heads are provided, so that the device will readily remove bolts even when the heads are broken off.

Further objects are to provide a device of 10 the type outlined above in which interchangeable jaws are provided for engaging work of different types, and in which a jointed handle is provided which may be operated to force a cam or conical member between the 15 cam faces of the jaws to force them into binding engagement and cause their serrated edges to bite into the bolt or pin, and further to so construct the device that the handle may be swung to the side when needed, either 20 for ease in manipulation or for greater leverage.

Embodiments of the invention are shown in the accompanying drawings in which:

Figure 1 is a side elevation of the device 25 with parts broken away and in section;

Figure 2 is a sectional view on the line 2-2 of Figure 1;

Figure 3 shows a further form of jaw.

Referring to the drawings, it will be 30 seen that the device comprises a body portion having a pair of spaced U-shaped arms 1 joined to a head 2. A relatively large screw 3 is threaded through the head 2 and carries a conical head 4 at its outer end. The inner 35 end of the screw is pivoted, as indicated at 5, to a T-shaped handle 6 so that the screw may be rotated either by gripping the handle while in line with the screw or else by rocking the handle laterally of the screw and thereby 40 obtaining greater leverage.

Between the arms 1 of the device a pair 45 of jaw members 7 are pivoted upon removable screws 8 and are urged apart by means of a U-shaped spring 9. These members are in reality jaws and are provided with grip-

ping portions 10 and cam portions 11. The jaws, as shown in Figures 1 and 2, may be provided with slightly arched or rounded faces provided with serrations, as shown most clearly in Figure 2.

In using the device, the jaws are slipped 50 over the object to be removed and thereafter the screw is screwed inwardly, thus forcing the cam faces of the jaws apart and causing the jaws to actually bite into the member to 55 be removed.

Other forms of jaws may be used, for instance, as shown in Figure 1, alligator or elongated jaws, indicated in dotted lines at 12, may be employed. In addition to this, the 60 form of jaw indicated in Figure 3 by the reference character 13 may be employed. This jaw is formed by bending the jaw portion over or offsetting it with reference to the plane of the body portion 14. The body portion is provided with a cam face 15 similar to the cam 65 faces 11, previously described. The jaw 13 may be provided with a straight row of serrations 16.

It will be seen that a simple type of combination vise and clamping tool has been 70 shown and it will be seen further that the device may be manipulated to engage widely different types of work and to securely hold the work locked to the jaws so that bolts may 75 be removed even though their heads may be broken off. Further, the device may engage pins, keys, or other members with the utmost ease.

Although the invention has been described 80 in considerable detail, such description is intended as illustrative rather than limiting as the invention may be variously embodied and as the scope of such invention is to be determined as claimed.

I claim:

A gripping tool comprising spaced U-shaped arms, a head joining said arms at one end, a relatively large screw threaded through the head, a conical end on said screw between 90

the arms, a T-shaped handle pivoted to the end of said screw, a pair of jaw members pivotally mounted between said arms, gripping jaws at the outer ends of the jaw members, cam portions at the inner ends of said jaw members, rounded serrated faces on said jaws and a U-shaped spring arranged between said jaw members with its ends engaging the gripping jaws to normally urge them apart.

5 ¹⁰ In testimony that I claim the foregoing I have hereunto set my hand at Merrill, in the county of Lincoln, and State of Wisconsin.

AUSTIN A. BENEDICT.
